UNITED STATES PATENT OFFICE

92,835

DESIGN FOR A GAME BOARD

Marion Brown, Chicago, Ill., and Frank J.
Prindiville, Detroit, Mich.

Application March 30, 1934, Serial No. 51,269

Term of patent 3½ years

To all whom it may concern:

Be it known that we, MARION BROWN, residing at Chicago, in the county of Cook and State of Illinois, and FRANK J. PRINDIVILLE, residing at Detroit, in the county of Wayne and State of Michigan, both citizens of the United States, have invented a new, original, and ornamental Design for a Game Board, of which the following is a specification, reference being had to the accompanying drawing, forming a part thereof.

Fig. 1 is a top plan view of a game board showing our new design, and

Fig. 2 is an edge elevation thereof.

We claim:

The ornamental design for a game board substantially as shown.

MARION BROWN.
FRANK J. PRINDIVILLE.
